Patented Feb. 1, 1921.

UNITED STATES PATENT OFFICE.

HUBBARD N. JOSLEYN, OF SYRACUSE, NEW YORK, ASSIGNOR TO REMINGTON TYPE-
WRITER COMPANY, OF ILION, NEW YORK, A CORPORATION OF NEW YORK.

TYPEWRITING-MACHINE.

1,367,145.

Specification of Letters Patent.

Patented Feb. 1, 1921.

Application filed June 23, 1915. Serial No. 35,838.

To all whom it may concern:

Be it known that I, HUBBARD N. JOSLEYN, citizen of the United States, and resident of Syracuse, in the county of Onondaga and State of New York, have invented certain new and useful Improvements in Type-writing-Machines, of which the following is a specification.

My present invention relates to connecting devices between disconnectible parts of typewriting machines and its general object is to provide new and improved devices of the character specified and which promote noiselessness and ease of operation. 10 More specifically stated the object of my invention is to provide automatic means for disconnecting and separating pawl and ratchet connecting devices which while they may be employed in various constructions 15 are preferably embodied in the connections between the spring drum and the ribbon mechanism of a typewriting machine so that they are effective to connect the ribbon feeding devices with the spring drum during 20 movement of the carriage in one direction; but during the return or reverse movement, the pawl and ratchet devices are automatically entirely disconnected, thus eliminating the noise due to the clicking or scraping 25 of the pawl idly over the ratchet teeth and also doing away with the friction. 30

To the above and other ends my present invention consists in the features of construction, combinations of devices and arrangements of parts hereinafter described and particularly pointed out in the claims. 35

In the accompanying drawings which illustrate the preferred form of my present invention,

40 Figure 1 is a front to rear vertical sectional view of so much of a Monarch typewriting machine as is necessary to a complete understanding of said invention which is embodied in said machine.

45 Fig. 2 is an enlarged face view of the spring drum and associated parts.

Fig. 3 is a vertical sectional view taken on a plane indicated by the dotted line in Fig. 2 and looking in the direction of the 50 arrow.

Fig. 4 is a fragmentary face view showing the pawl and ratchet devices in different relationships from those shown in Fig. 2.

55 Fig. 5 is a plan view partly in section showing the pawl and ratchet devices.

As shown in the drawings the main frame of the machine comprises a base 1, posts 2 and a top plate 3 above which are oppositely grooved fixed track-ways 4 that coöperate through anti-friction balls 5 with the slide bar of a carriage 6 on which is mounted a platen 7. Coöperative with the front face of the platen are type bars 8 pivotally mounted on a segment 9, each type bar being connected by a link 10 with a sub-lever 11 pivoted to a key lever 12. The set of key levers coöperate with a fulcrum plate 13 mounted in the rear part of the base and each is adapted to depress a universal bar 14 that is carried by a frame having a rod or shaft 15 supported from the sides of the base. Comprised in said frame is a rearwardly extending arm 16 that is connected by a link or device 17 with a dog rocker 18 pivotally supported on a stationary bracket 19 and having pivoted near its upper end two escapement dogs 20 and 21 that coöperate with a toothed escapement wheel 22. Operatively connected with the escapement wheel 22 by devices including a shaft (not shown) having a fixed bearing is a feed pinion 23 that is normally engaged by a feed rack 24 supported on arms 25 that are pivoted on the carriage 6.

A pin or device 26 that extends downward from the right-hand end portion of the carriage is connected by a band or strap 27 with a cylindrical drum or casing 28, one end of the band 27 being screwed or otherwise secured to the periphery or outer face of the drum 28 while the opposite end of the band is detachably connected to the pin 26. Said drum 28 is open at its front side and has fixed to its rear side by screws 29 a smaller drum 30 containing a coiled main spring 31, the outer end of which is fastened to the drum 30 and the inner end to a horizontal shaft 32 which bears in a portion 19^a of the bracket 19. Mounted on a threaded portion of the shaft 32 behind the bracket or bearing 19^a is a ratchet wheel 34 which has a pin and slot connection with said shaft that prevents relative rotation between them. Said ratchet wheel is clamped against a shouldered portion of the shaft by a nut 35, thus fixing the relationship between the shaft and the ratchet wheel. Coöperative with the ratchet wheel 34 is a double toothed pawl 36 pivoted on the bracket 19 and provided with a finger 110

piece 37 which may be manipulated to vary the rotative position of the shaft and so regulate the tension of the motor or main spring 31. Normally the shaft is locked 5 against rotation by the coöperation of the pawl 36 with the ratchet wheel 34. Rigid with the drum or casing 28 is a forwardly projecting hub 38 that bears on the forward, reduced end portion of the shaft 32, said hub 10 portion being provided with a flange 39 and having threaded into its front end a headed screw 40. Loosely mounted on the hub 38 and confined between the flange 39 and the head of the screw 40 is a beveled pinion 41 having a rearward extension or hub 42 on which are mounted face to face two ratchet wheels 43 and 44, the forward ratchet wheel 43 being slightly dished so that the sets of ratchet teeth are separated a little from each 15 other. The rear end of the hub 42 is spread or upset, thus clamping the ratchet wheels 43 and 44 tightly between the upset portion and the back face of the pinion proper 41. In effect the gear and the two ratchet wheels 20 operate as a single piece, being capable of turning as one on the hub 38.

Means to be hereinafter described and embodying the gist of my present invention are provided for connecting the ratchet wheel 44 with the drum 28 so as to cause the ratchet wheel to turn with the drum during letter space movements of the carriage. This movement of the ratchet wheel is transmitted to the pinion 41 which is rigid 30 with it and from the pinion to the ribbon feeding mechanism. A pawl member or gravity detent 45 coöperates with the ratchet wheel 43 to prevent backward rotation of said ratchet wheel and the parts rigid therewith. Said detent terminates at its free or left hand end in a rearwardly bent tooth portion which overlies the ratchet wheel 43 and coöperates therewith. At its right-hand end the detent is provided with a 35 U-shaped bearing portion 46 perforated to bear on a screw pin 47 secured in a portion 49 of the bracket 19 just below the top plate.

The inking ribbon 48 is wound on spools 50 arranged forward of the top plate, one at each side of the machine. Midway between the spools the ribbon is threaded through a ribbon vibrator 50 which is slidably mounted on a guide 51. The stem of the vibrator is pivotally connected with an operating lever 52 which is fulcrumed at 53 on a bearing member 54 depending from the top plate. The rear arm of the operating lever has a slot 55 which is engaged by 58 an actuating pin 56 projecting laterally from the upper end of the link 57, said link being pivotally connected to the arm 16 of the universal bar frame. The construction is such that when the universal bar 14 is 63 depressed the link 57 will actuate the oper-

ating lever 52 which will raise the vibrator 50 and bring the ribbon opposite the printing point at the front of the platen 7 and into the path of the actuated type bar. The position of the operating pin 56 lengthwise of the slot 55 may be varied in the usual way, by devices comprising the adjustable rotary member 57, to vary the widthwise portion of the ribbon that is presented to the types. Each ribbon spool 49 is mounted 75 on the upper end of a vertical shaft 58 having a stationary bearing 59. Fixed to the lower end of each shaft 58 is a small beveled gear wheel 60 with which constantly meshes a beveled pinion 61 fixed to the forward end of a shaft 62 which bears in lugs 63 depending from the top plate and extends horizontally rearward. Fixed to the rear end of each shaft 62 is a beveled gear wheel 64 which is adapted to mesh with 80 one of a pair of beveled gear wheels 65 that are fixed to a ribbon driving shaft 66 extending from side to side of the machine below the top plate and mounted in bearings depending therefrom. The driving shaft 66 is movable endwise to bring either gear wheel 65 into mesh with its companion gear 64 and thereby connect the associate ribbon spool with the ribbon driving shaft, the other ribbon spool at the same time being disconnected therefrom. The driving shaft is connected with the beveled pinion 41 by a beveled pinion 67 which is slidably mounted on the driving shaft 66 but is so connected therewith that said shaft will 85 always be turned when said pinion is turned, although the shaft may move endwise without affecting the pinion 67 which always remains in mesh with the pinion 41. By moving the shaft 66 back and forth 90 endwise which may be done either by hand or automatically in the usual way, the ribbon spools may be connected in alternation to the ribbon by the driving shaft so that the direction of longitudinal feed of the 95 ribbon may be reversed. All the parts hereinbefore described are or may be such as are common to the Monarch typewriting machine.

The present exemplification of my invention embodies novel pawl mechanism for connecting the spring drum or driving movable element through the ratchet wheel 44 with the ribbon driving pinion or driven movable element 41, this mechanism being 110 effective when the drum turns or rotates in the direction of the arrow (Fig. 2) to draw the carriage leftward; but said pawl mechanism automatically separates from the ratchet wheel 44 when the direction of rotation of the spring drum is reversed and the carriage is restored or moved backward from left to right. Said pawl mechanism comprises a pawl 68 pivoted on a headed shoulder screw 69 which is threaded into the 115

bottom or vertical portion of the drum 28 near its periphery, a washer 70 being interposed between the bottom of the drum 28 and the pawl as best shown in Fig. 3. The 5 construction is such that the pawl is always maintained in the plane of the ratchet wheel 44 although it may turn on its pivot so as to engage with and disengage from the teeth of said ratchet wheel. Interposed between 10 the tooth of the pawl 68 and its pivot 69 is a bow spring 71, the loop of the spring extending to the opposite side of the pivotal axis of the pawl from the pawl tooth. One 15 end of the spring is provided with an ear 72 which is perforated to receive a headed screw 73, said screw being threaded into the pawl 68 between its pivot and its tooth or free end and thus fixedly clamping one end of the spring to said pawl. The opposite or 20 free end of the spring is bent slightly downward as indicated at 74 so as to engage with the teeth of the ratchet wheel 44. The constant tendency of the spring is to expand, that is, its opposite sides or blades tend 25 constantly to move away from each other. This tendency is normally overcome by the greater force of the main spring 31 contained within the spring drum so that during 30 movements of the spring drum in the direction of the arrow in Fig. 2 to draw the carriage leftward, the spring 71 is contracted and the tooth of the pawl 68 is operative or engaged with the ratchet wheel 44 shown in Fig. 2. The instant, however, that the 35 pull of the main spring 31 is withdrawn, which occurs when the carriage is started toward the right and the direction of rotation of the spring drum is reversed as indicated by the arrow in Fig. 4, the bow spring 40 71 will expand and force the pawl 68 out of engagement with the ratchet wheel 44. At the same time that the sides of the spring 71 separate further, the spring as a whole, since it is rigidly connected to the pawl, will turn 45 about the axis of the pawl as the pawl itself turns and said spring will, as a whole, approach closer to the ratchet wheel 44. As a result of the initial turning of the spring drum in reverse direction the parts will be 50 brought to the position shown in Fig. 4. Thus the pawl 68 is automatically entirely disconnected from the ratchet wheel and the connection between the spring drum and the ribbon feeding devices or mechanism is automatically 55 broken, so that the noise due to the clicking of the pawl, heretofore employed, over the ratchet wheel during return movements of the carriage is avoided, the only sound from the pawl mechanism being 60 that due to the slight click of the free end portion of the spring 71 over the teeth of the ratchet wheel 44. This sound is so slight as to be scarcely noticeable. At the end of the return movement of the carriage and the 65 withdrawal of rightward pressure by the

operator thereagainst, the main spring operates automatically to restore the pawl 68 to the Fig. 2 or operative position, so that during leftward movements the ribbon feeding mechanism will again be operatively connected with the spring drum. 70

Thus it will be seen that the novel pawl and ratchet mechanism or connections between the carriage power or motor and the ribbon feeding mechanism is rendered automatically operative and inoperative in alternation in correspondence with movements of the carriage and the spring drum. Said mechanism embodies a pawl and spring means constantly tending to hold or turn 75 said pawl out of engagement with its ratchet wheel, said spring means being overcome by the turning movement or rotation of the spring drum or movable element in one direction, and being rendered effective by the 80 turning of the spring drum or element in the opposite direction. While it is preferable as shown to employ said spring means itself as a connection between the pawl and its ratchet wheel, this construction may be 85 changed without departing from some of the principles of my invention.

It will be observed further that by my present invention there are provided two movable elements, viz., the casing or drum that 90 is turned by the main spring and the beveled pinion 41, in combination with pawl and ratchet connections between said elements, means, viz., the bow or loop spring in the present instance, which engages said ratchet 95 and constantly tends to separate said pawl and ratchet connections, and means, viz., the carriage main spring, which operates during certain movements of one of said movable elements to overcome the spring and force 100 the pawl and ratchet to operatively engage; that the certain movements referred to are rotary movements of the spring drum in the direction in which it turns to draw the carriage in printing direction; that when the 105 carriage is restored and the element or spring drum moves oppositely or turns in the reverse direction the loop spring becomes effective to separate the pawl entirely from the ratchet wheel; that the free end of said 110 spring constantly engages with the teeth of said ratchet wheel; that ribbon feeding mechanism is constantly connected to the driven element or beveled pinion 41; that the ratchet wheel is co-axial with the spring 115 drum or carriage motor; and that the ribbon mechanism is constantly connected with said 120 ratchet wheel.

Various changes may be made without departing from the spirit and scope of my invention. 125

What I claim as new and desire to secure by Letters Patent, is:—

1. In a typewriting machine, the combination of two movable elements, pawl and 130

- ratchet connections between said elements, said connections when engaged with each other moving with said two movable elements, and means constantly tending to separate said pawl and ratchet connections, one of said movable elements operating automatically to overcome the tendency of said means and to maintain said pawl and ratchet connections normally operatively engaged.
- 10 2. In a typewriting machine, the combination of two movable elements, pawl and ratchet connections between said elements, said connections when engaged with each other moving with said two movable elements, and a spring constantly tending to separate the pawl from the ratchet, one of said movable elements operating automatically to overcome the tendency of said spring and to maintain said pawl and ratchet connections normally operatively engaged.
- 15 3. In a typewriting machine, the combination of two movable elements, automatically engageable and disengageable pawl and ratchet devices between said elements, said devices being normally engaged and when engaged with each other moving with said two movable elements in one direction of rotation, and means constantly tending to separate said pawl and ratchet devices, said 20 means being overcome by one of said elements moving in one direction but allowed to exercise its said tendency when said element is moving in the opposite direction.
4. In a typewriting machine, the combination of two movable elements, pawl and ratchet connections between said elements, said connections being automatically and normally engaged with each other and when so engaged with each other moving with said 25 two movable elements, and means engaging the ratchet and constantly tending to separate the pawl from the ratchet, said means being overcome when one of said two movable elements is moving in one direction but 30 allowed to exercise its tendency to separate the pawl from the ratchet when said movable element is moving in the opposite direction.
5. In a typewriting machine, the combination of a motor, motor driven mechanism, connecting devices comprising a pawl and ratchet wheel between said motor and said mechanism, both said connecting devices when operatively engaged moving with said motor, and means constantly engaging with 35 said ratchet wheel and tending to separate said pawl therefrom, said motor being effective automatically to overcome said means and normally maintain said pawl in engagement with said ratchet wheel.
- 40 6. In a typewriting machine, the combination of driving mechanism, driven mechanism, devices comprising a pawl and a ratchet wheel for connecting said driven mechanism with said driving mechanism, said pawl and said ratchet wheel when en-

gaged both moving when said driving mechanism moves, and a spring tending constantly to separate said pawl from said ratchet wheel, said driving mechanism automatically overcoming said spring and normally maintaining said pawl in effective engagement with said ratchet wheel.

7. In a typewriting machine, the combination of a spring drum, a pawl pivoted thereon, a ratchet wheel with which said pawl cooperates, said pawl and said ratchet wheel when engaged both moving when said spring drum moves, driven mechanism operatively connected with said ratchet wheel and a spring tending constantly to throw said pawl 75 out of engagement with said ratchet wheel, said spring drum being automatically effective to overcome said spring and normally maintain said pawl in operative engagement with said ratchet wheel.

8. In a typewriting machine, the combination of a spring drum, a ratchet wheel coaxial with said spring drum, a pawl pivoted on said spring drum for coöperation with said ratchet wheel, said pawl and said spring 80 drum when coöperative both moving when said spring drum moves, driven mechanism constantly connected with said ratchet wheel, and a spring tending constantly to throw said pawl out of engagement with 85 said ratchet wheel, said spring drum being automatically effective to overcome said spring and normally maintain said pawl in operative engagement with said ratchet wheel.

9. In a typewriting machine, the combination of a spring drum, a pawl carried thereby, a ratchet wheel for coöperation with said pawl, and a bow spring secured at one end to said pawl, the other end of said spring 90 engaging with the teeth of said ratchet wheel, said bow spring being overcome by said spring drum which maintains said pawl 95 normally engaged with said ratchet wheel.

10. In a typewriting machine, the combination of a spring drum, a pawl pivoted thereon, driven mechanism, a ratchet wheel connected to said mechanism and coöperating with said pawl, and a bow spring secured at one end to said pawl, the other 100 end of said spring engaging with the teeth of said ratchet wheel, said spring drum normally forcing the leaves of said bow spring 105 to contract and thus to maintain said pawl normally in coöperative engagement with said ratchet wheel, the leaves of said bow spring expanding and throwing said pawl 110 out of engagement with said ratchet wheel when the direction of rotation of the spring 115 drum is reversed.

11. In mechanism of the character described, the combination of a spring drum, a pawl pivoted thereon, a ratchet wheel coöperative with said pawl, a bow spring secured at one end to said pawl and having its 120

other end engaging with said ratchet wheel, a second ratchet wheel rigid with said first ratchet wheel, and a detent pawl coöperative with said second ratchet wheel to prevent backward turning of both of said ratchet wheels.

12. In a typewriting machine, the combination of a spring drum; a pawl pivoted thereon; driven mechanism comprising a ratchet wheel for coöperation with said pawl, and a bow spring secured at one end to said pawl, the other end of said spring engaging with the teeth of said ratchet wheel; a second ratchet wheel rigid with said first ratchet wheel; and a detent pawl coöperative with said second ratchet wheel to prevent backward turning of both of said ratchet wheels.

13. In a typewriting machine, the combination of two movable elements, pawl and ratchet connections between said elements, said connections when engaged with each other moving with said two movable elements, means constantly tending to separate said pawl and ratchet connections, and means constantly connected with one of said movable elements and normally operating to overcome automatically the tendency of said first recited means and to maintain said pawl and ratchet connections normally operatively engaged.

14. In a typewriting machine, the combination of two movable elements, pawl and ratchet connections between said elements, said connections when engaged with each other moving with said two movable elements, a spring constantly tending to separate the pawl from the ratchet, and means constantly connected with one of said movable elements and normally operating to overcome automatically the tendency of said spring and to maintain said pawl and ratchet normally operatively engaged.

15. In a typewriting machine, the combination of two movable elements, pawl and ratchet connections between said elements, said connections when engaged with each other moving with said two movable elements, means engaging the ratchet and constantly tending to separate the pawl from the ratchet, and means normally operating to overcome automatically the tendency of said first recited means and to force said pawl normally to engage operatively with said ratchet.

Signed at Syracuse, in the county of Onondaga, and State of New York, this 21st day of June, A. D. 1915.

HUBBARD N. JOSLEYN.
